UNITED STATES PATENT OFFICE.

CHARLES FREDERICK HESS, OF SCRANTON, PENNSYLVANIA.

COIN SEPARATING, COUNTING, AND PACKAGING MACHINE.

No. 857,172.

Specification of Letters Patent.

Patented June 18, 1907.

Application filed October 29, 1906. Serial No. 341,161.

To all whom it may concern:

Be it known that I, CHARLES FREDERICK HESS, a citizen of the United States, residing at Scranton, in the county of Lackawanna and State of Pennsylvania, have invented certain new and useful Improvements in Coin Separating, Counting, and Packaging Machines; and I do hereby declare the following to be a full, clear, and exact description of the same, reference being had to the accompanying drawings, forming a part of this specification, and to the figures and letters of reference marked thereon.

This invention relates to the type of machine disclosed in my prior patent No. 811,559, dated February 6th, 1906, and like the machine of said patent, the present machine is designed to receive in bulk coins of all denominations capable of being separated by the machine and to quickly and effectually separate and deposit the same in wrappers or packages each containing a predetermined number of coins, the coins of each denomination being counted whereby the value of the separated coins may be quickly determined.

The novelty of the present invention resides more particularly in the mechanism for discharging, counting and packaging the separated coins and in certain novel details of construction and combinations and arrangements of parts all as will be now described and pointed out particularly in the appended claims.

In the accompanying drawings—Figure 1 is a perspective view of the lower portion of a machine embodying the present improvements, certain of the parts being omitted to prevent confusion in the drawing. Fig. 2 is a perspective but taken from an elevated point of view to show the arrangement of certain of the internal parts. Fig. 3 is a plan view of one of the carrying and separating wheels together with the coin discharging means. Fig. 4 is a vertical section through the parts shown in Fig. 3. Fig. 5 is a front elevation and Fig. 6 a sectional side elevation of one of the counting mechanisms and coin chutes. Fig. 7 is a vertical section through the upper portion of one of the coin chutes. Fig. 8 is a detail horizontal section through the counting mechanism and upper end of one of the coin chutes. Fig. 9 is a top plan and Fig. 10 a side elevation of the preferred form of receiver or coin package car-

rier and escapement for controlling the feed of the same.

Similar letters of reference in the several figures indicate like parts.

As heretofore, the present machine preferably embodies superposed sections A' properly secured together and having bearings for a central shaft B on which the coin carriers or wheels C are mounted so as to be capable of rotation. Power may be transmitted to the shaft B from any suitable source through a transverse shaft B' geared to shaft B and extending out at one side of the machine.

Each section A embodies concentric walls 70 a between which the coins pass and by which said coins are guided to the proper receptacles and apertures in the carriers. The carriers extend through the inner annular wall and into proximity to the outer wall or into 75 position to have their radially arranged receptacles shown at c in Fig. 3, register in succession with coin discharge apertures c' in the outer wall opposite the coin chutes D.

In each receptacle of all the carriers save 80 the lowermost one is an aperture c² for the passage of all coins smaller than the coins adapted to be handled by the particular carrier thus the smaller coins drop through the carriers in succession until one is reached 85 where they will seat in the receptacles without passing through the apertures.

The discharging mechanism of the present invention consists of radially movable dischargers or pushers E working in the receptacles and adapted to be advanced and retracted by inclines or cam surfaces preferably in the form of cam rings E' supported by brackets E' from the inner walls a of the sections and adapted to receive between 90 them rollers or projections e on the pushers or dischargers E.

Two inclines are preferably provided in the cam rings, one at F for advancing the dischargers a sufficient distance to partially 100 discharge the coin and cause it to project a sufficient distance to operate the counting mechanism, chute gate and package controlling mechanism as will be presently described and the other at F' for advancing the dischargers a sufficient distance to completely 105 discharge the coin into the chute. At F² a reverse incline is provided for retracting the pushers and from that point around to the incline F the cam rings are preferably con- 110

centric and serve to retain the pushers or dischargers in their retracted positions.

When the coins are in their partially discharged position they will as shown in Fig. 8 at the left, be in position to engage and operate a pawl carrying lever G pivoted at g in a bracket and carrying a pawl H adapted to coöperate with a ratchet wheel H', each coin operating to advance the wheel a predetermined distance, one tooth for instance.

The wheel H' is a master wheel in a train which controls the counter, the feed of the coin receivers or wrappers and a chute gate for directing the coins into the proper receiver.

The counter may be of any ordinary construction but as shown consists of a dial I mounted in inclined position for convenience in reading and having a pointer I' which through bevel gears i , i' , i^2 and i^3 is connected with the ratchet wheel H' so as to be moved over the dial for indicating the number of coins discharged.

The wheel i' also meshes with a larger gear wheel K on which are removably but rigidly mounted cams K', K², for controlling or operating the chute gate and wrapper carriage escapement. For operating or controlling both these parts, levers M are pivotally mounted in the bracket in position to rest at one end against the cams and at the other end to receive rods k k' extending downwardly from connection with the parts to be operated.

By reference to Figs. 7 and 8 it will be seen that the coin chutes D are curved at the upper end to face the discharge apertures and each has a horizontally curved lip n adapted to engage the coins at a point behind their greatest diameter and direct or deflect them into the chute as shown by the dotted representation of a coin at the right in Fig. 8.

In the rapid operation of the machine the coins are discharged in such rapid succession that it is difficult to change from one receiver to another and insure the placing of the proper number in each package. To overcome this difficulty the chutes are branched or each provided with two channels or ducts one or the other of which may be in proper registry with a receiver at all times and a movable gate is provided which is of such construction that it may be operated with certainty between the discharge of coins even though they follow each other with great rapidity. This gate lettered N' in the drawings is vertically movable, being guided in slots N² in the sides of the chute and is at its upper end adapted to shift vertically from top to bottom or bottom to top of the discharge aperture as shown by the full and dotted lines in Fig. 7. In one position the gate forms the bottom of one duct or channel and in the other position the top of the other duct or channel and the possibility of coins

lodging in either duct is reduced to a minimum by bifurcating the lower end of the gate at N² to embrace the upper end of the partition between the ducts or channels thus forming passages without ledges.

As a precaution against coins striking the upper edge of the gate itself the width of the gate is reduced at the end by cutting away the forward corner as shown at N⁴ in Fig. 8.

The rod k extending down from one of the levers M is connected with the gate through the spring pressed lever k² and connecting rod k³ whereby the cam K' will shift the gate at predetermined intervals to direct the coins into one channel or the other as the case may be and the time of the cam and counter are so correlated that the gate will be shifted only when a predetermined number of coins have been discharged into one channel and directed by it into the proper wrapper or receiver.

Obviously the receivers may be of any character, but it is preferred that they shall be in the form of wrappers one end being left open and adapted to be closed by hand after the coins are in place. The wrappers are preferably mounted in carriages adapted to hold any desired number and mounted to run on substantially horizontal tracks or ways P located below the level of the body of the separator. Two of these carriages Q with the tracks on which they run are shown, in Fig. 1, the same carriages with associated parts being shown in plan and elevation on a larger scale in Figs. 9 and 10.

Each carriage consists of a number of tubular wrapper holders Q' held together side by side by the frame Q and adapted to be supported by rollers q working on the tracks P.

The carriages are advanced along the ways by pushers R (Fig. 1) to which weights R' are connected by flexible connectors R². This forward movement is controlled by an escapement operated by the rod k' and cam K². In the construction illustrated a spring pressed lever S is pivoted at one end on a fixed support S' located between adjacent tracks adapted to carry carriages for receiving coins of the same denomination, and at the opposite end it is connected with the rod k' so as to be reciprocated in a vertical plane.

Oppositely arranged spring pressed escapement dogs S² S³ are pivotally mounted on opposite sides of the lever S in position to engage with teeth T on the carriages Q and in connection with stop projections S⁴, S⁵ form escapements for said carriages operating to alternately release the carriages one when the lever moves up and the other when the lever moves down but both carriages when at rest are in position for coins to pass from the chute into one of the receivers or wrappers.

The cam K' is set to operate the escapement a short time after the cam K operates.

- the chute gate and the arrangement is such that upon such movement of the escapement the carriage then receiving coins shall be held stationary and the carriage having the last 5 previously filled wrapper shall be advanced, thus there is no period where the coins can by any possibility catch and jam during the movement of the carriages and a receiver is always in position for the reception of coins.
- 10 In the operation of the apparatus the coins are distributed to the carriers by spring pressed brushes X Fig. 2 and should it be desired at any time to remove the receivers containing all the coins of a given batch or bulk 15 and return the counter to zero, the latter may be advanced by turning the knob I^o on the pointers, such turning movement also advancing the coins and operating the escapement to advance the carriages containing 20 coins to a point beyond the chute where they may be removed.

While the drawings show only two carriages and ways therefor and two coin chutes together with sections of the machine corresponding thereto, it will be understood that 25 sections, chute, carriages and ways therefor are usually provided to permit of the separation and packaging of coins ranging from dollar to pennies, but the additional parts necessary, are merely duplicates of those shown and hence illustration of the complete machine is unnecessary and undesirable for a full and clear understanding of the present invention.

30 By the provision of cams for both projecting and retracting the dischargers for the coins, not only is the noise incident to the discharge of the coins eliminated but wear on the coins is reduced and the use of a positively acting counting mechanism rendered practical without the use of special transfer mechanism.

While the machine as shown is particularly designed for packaging coins in receivers 45 adapted to contain but few coins it is obvious that the proportions or number of wheels in the gear train and size of the coins may be changed to permit the packaging of larger numbers of coins in larger receivers or bags.

50 Having thus described my invention what I claim as new and desire to secure by Letters Patent, is:—

1. In a device such as described, the combination with a substantially horizontal rotary carrier having peripherally disposed coin receptacles in its upper face, of coin dischargers working in said receptacles radially of the carrier, a cam for advancing and a cam for retracting said dischargers.
- 60 2. In a device such as described, the combination with a rotary carrier having peripherally disposed coin receptacles in its upper face and an aperture in each receptacle for the passage of coins of smaller diameter than those adapted to be held in the receptacles, of

coin dischargers working in said receptacles radially of the carrier, a cam face for advancing and a cam face retracting said dischargers.

3. In a device such as described, the combination with a rotary carrier having peripherally disposed coin receptacles in its upper face and an aperture in each receptacle for the passage of coins of smaller diameter than those adapted to be held by the receptacles, 70 of coin dischargers working in said receptacles radially of the carrier, a cam face for partially advancing said dischargers and holding them in such position during a portion of the revolution of the carrier, a cam 80 face for completing the advance movement of the dischargers and means for retracting the dischargers.

4. In a device such as described, the combination with a rotary carrier having peripherally disposed coin receptacles in its upper face and an aperture in each receptacle for the passage of coins of smaller diameter than those adapted to be held in the receptacles, 85 of coin dischargers working in said receptacles radially of the carrier, a cam face for partially advancing said dischargers a cam face for completing the advance of the dischargers and a cam face for retracting the dischargers.

5. In a device such as described, the combination with a rotary carrier having peripherally disposed coin receptacles in its upper face and an aperture in each receptacle for the passage of coins of smaller diameter than those adapted to be held by the receptacle, 90 of coin dischargers working in said receptacles and having projections thereon, fixed cam faces forming a guide way for said projections and having concentric and non-concentric portions, the latter being formed to first partially advance, then fully advance and finally retract the dischargers and to permit of a dwell when the dischargers are partially advanced.

6. In an apparatus such as described, the combination with a plurality of horizontally-rotatable coin carriers and means for discharging coins radially therefrom, of a plurality of movable coin receivers, parallel horizontal ways on which the receivers are mounted below the rotary carriers, chutes for directing the discharged coins to the receivers and mechanism operated by the discharged coins for controlling the movement of the receivers.

7. In an apparatus such as described, the combination with a coin carrier having receptacles for coins therein and means for successively discharging the coins from the receptacles, of a plurality of channels for directing the discharged coins and a coin operated gate for determining the channel into which the coin shall pass.

8. In an apparatus such as described the

combination with a rotary coin carrier having receptacles for coins therein and means for successively discharging the coins from the receptacles, of a plurality of channels for directing the discharged coins to receivers, and a coin operated gate in proximity to the carrier for determining the channel into which the coin shall pass.

9. In an apparatus such as described, the combination with a rotary coin carrier having coin receptacles therein and means for successively discharging the coins therefrom, of a plurality of channels for directing the discharged coins to receivers, a gate for determining the channel, into which the coin shall pass and a gate operating mechanism, itself operated by the coins to shift the gate upon the passage of a predetermined number of coins.

10. In an apparatus such as described the combination with a rotary coin carrier having coin receptacles therein and means for successively discharging the coins therefrom, of a plurality of channels for directing the discharged coins to receivers, means for determining the channel through which the coins shall pass, independently movable receivers into which the channels discharge and means whereby said receivers are fed alternately.

11. In a coin packaging apparatus, the combination with coin carrying and discharging mechanism for feeding the coins in succession, of a plurality of independently movable receivers, means for feeding them alternately and means for directing the discharged coins into the receivers alternately and during their periods of rest.

12. In a coin packaging apparatus the combination with coin carrying and discharging mechanism for feeding the coins in succession, of a plurality of independently movable receivers, a coin controlled feeding mechanism for feeding them alternately and coin controlled means for directing the discharged coins into the receivers alternately and during their periods of rest.

13. In a coin packaging apparatus, the combination with coin carrying and discharging mechanism for feeding the coins in succession, of a plurality of independently movable groups of receivers, a feeding mechanism for feeding the groups alternately, controlled by the coins to feed the receivers when a predetermined number of coins have been discharged and coin controlled means for directing the discharged coins into the receivers alternately and during their periods of rest.

14. In an apparatus such as described, the combination with the rotary carrier having coin receptacles therein and radially movable means for first partially and then fully discharging the coins radially from the

receptacles in succession, of a coin counter operated by the partially discharged coins and a coin chute with which the receptacles register after passing the counter to receive the discharged coins.

15. In an apparatus such as described, the combination with the rotary carrier having coin receptacles therein and means for first partially and then fully discharging the coins radially therefrom in succession, of a coin counter operated by the partially discharged coins, a plurality of coin channels a gate for determining which channel the coins shall enter and a cam for operating said gate also operated by the partially discharged coin.

16. In an apparatus such as described the combination with the rotary carrier having coin receptacles therein, means for first partially and then fully discharging the coins radially therefrom in succession, and independently movable coin receivers for the discharged coins, of means for feeding the receivers alternately and means for directing the discharged coins into one or the other of said receivers, both controlled by the partially discharged coins.

17. In an apparatus such as described the combination with the coin carrier and mechanism for discharging the coins in succession therefrom, of a plurality of independently movable groups of receivers, oppositely arranged escapements for feeding said groups alternately and mechanism operated by the coins for reciprocating said escapements.

18. In an apparatus such as described the combination with a plurality of superposed carriers having radial receptacles therein and means for discharging the coins radially from the chambers, of a plurality of movable receivers and horizontal ways therefor located below the carriers and chutes for directing the discharged coins from the carriers to the receivers.

19. In an apparatus such as described the combination with the carrier having radial receptacles therein and means for discharging the coins radially, of a coin chute having a lip extending toward the carrier and beyond the point of greatest diameter of the discharged coin.

20. In an apparatus such as described the combination with the carrier having radial receptacles therein and means for discharging the coins radially, of a coin chute having a lip curved to pass on the inner side of the discharged coin to deflect the same away from the carrier.
